COMBINED SAFETY CLAMP AND CAP FOR GAS JETS AND THE LIKE

Norman A. Rosentreter, 1415 Federal Road,
Houston, Tex.

Filed Sept. 25, 1962, Ser. No. 71,841

Term of patent 14 years

(Cl. D16—2)

FIGURE 1 is a perspective view of a combined safety clamp and cap for gas jets and the like showing my new design; the valve cock and nozzle members are shown in dotted lines for illustrative purposes only;

FIGURE 2 is a top plan view thereof;

FIGURE 3 is a side elevational view thereof; and

FIGURE 4 is an end elevational view thereof.

I claim:

The ornamental design for a combined safety clamp and cap for gas jets and the like, as shown and described.
